ABSTRACT OF THE DISCLOSURE

A device for the removal or application of links from chains, the device having a holding portion engageable with a link and a force applying portion pivoted to the holding portion and operative to apply force to a next adjacent link for placement or removal thereof.

BACKGROUND OF THE INVENTION

Field of the invention

This invention pertains to chain assembly and disassembly apparatus in the nature of pliers or similarly arranged devices wherein the elements are pivotally arranged with respect to one another.

Description of the prior art

Prior patents dealing with the general subject under consideration include United States Patents Nos. 1,785,946, 2,312,027, 2,467,279, 2,711,628, and 2,818,701. previously proposed tools of the general type under consideration have been subject to objection on the ground of limited functionality, most being useful only for chains of very specific types. Further, the prior art devices are difficult to use, and do not admit of the application of sufficient force to accomplish the required objectives.

SUMMARY OF THE INVENTION

In the handling of chains of certain types, it is necessary to the correct assembly and/or disassembly of the chain that the links thereof be moved relative to one another in a specific manner. Where the chain is of a flat link variety, the individual links normally comprise link frame sections with openings therein, and hinge sleeve portions on the opposite sides of the openings. These hinge sleeve portions are successively inter-engaged with one another, and the chains are often formed in endless arrangements in which they function as drive units between opposing sprocket wheels or in other, similar manners. The hinge elements are frictionally engaged with one another and it is often necessary to apply a substantial force in order to disengage the chain elements for replacement and also to connect new elements. The present invention provides means for the application of substantial force to the chain over and above that available with conventional pliers and the like.

A related object of the present invention is to supply a chain link plier wherein the force-applying portion is so arranged as to provide a direct linear movement of

2

the links with respect to one another while, at the same time, supplying a maximum mechanical advantage in the application of force to the links.

Another and related advantage of the present construction resides in the particular formation of the holding section of the device to engage a link in such manner as to permit the safe application of maximum force thereto with minimum danger to the user.

The invention comprehends a chain link handling device comprising a holding section engaging one of the links of the chain and a leverage section to apply or remove a next adjacent link, the device further including a support means for the holding assembly.

Additional objects and advantages of the invention will become apparent to those skilled in the art from a consideration of the following specification when read in conjunction with the annexed drawing.

BRIEF DESCRIPTION OF THE DRAWINGS

FIGURE 1 is a perspective view, partially foreshortened, showing a chain assembly and disassembly device constructed in accordance with the present invention;

FIGURE 2 is a partial perspective view of the device seen from an opposite side;

FIGURE 3 is a side elevational view;

FIGURE 4 is a top plan view;

FIGURE 5 is a front elevational view;

FIGURE 6 is a sectional view taken substantially on the section line 5—5 of FIGURE 4, looking in the direction of the arrows; and

FIGURE 7 is a perspective view showing another functional position of the device.

DESCRIPTION OF THE PREFERRED EMBODIMENTS

Referring to the drawing in greater detail, the chain assembly and disassembly device hereof is generally designated therein by reference numeral 10. The device 10 is useful in either the placement or the removal of links 12 from a chain. The specific form of the links is subject to some variance. A typical link of the type with which the invention is of maximum utility is best seen in FIGURE 1 and includes a frame portion having upper and lower sides 16 and 18. The frame further includes an inner hinge element 20 at one of its ends and an enlarged outer hinge element 22 at its opposite end. The side members and hinge elements define an opening 24 of substantially rectangular form, and the frame may further include outer sleeve sections 26 if desired. In an assembled chain (FIGURE 4) the inner sleeves 20 are engaged within the outer sleeves 22 of the succeeding links, the engagement being basically frictional. In the latter figure it will also be observed that placement or removal requires a specific inclination of the link to be applied or removed with respect to the succeeding link. The outer sections 26 are spaced in a vertical plane slightly offset from the sleeves as appears more fully below.

The device 10 has two main components. The first of these is a holding arm assembly 28 which includes a body section 30 and an extended handle section 32. The body section 30 has an outer end portion 34 having a forward edge 36 and shaped at said forward edge in such

manner as to be engageable within the opening 24 of one of the links in the manner indicated in FIGURES 1, 4 and 5. With the link so engaged, the hinge sections 26 and 22 thereof are laterally arranged with respect to the portion 34.

The outer end portion 34 of the body section includes a substantially flat upper side 38, and a substantially cylindrical stop lug 40 projects upwardly from the upper side at a location spaced a selected distance inwardly from the end edge 36 but in substantially flush relation to the inner side 41 of the end portion 34. The stop lug 40 is preferably of heavy stock and has a flat outer side 42 serving a function described in more detail below.

A support means for the device 10 is provided and comprises an inverted T-bar 44 which includes a stem 15 secured, as by welds 48, to the body section 30, and a cross bar 50 secured thereto. As best shown in FIGURE 3, the T-bar 44 projects from the body section 30 in a direction opposite to the direction of extension of the stop lug 40.

At a location substantially vertically aligned with the T-bar support 44, the body section 30 has a transverse opening therein through which a cross bolt or axle 52 is extended. The axle carries lock nuts 54 at its outer ends and may have optional intermediate spacers 56.

A second major component of the invention comprises a lever arm 58 which includes a work contact section 60 having an angular, distal portion 62 fixed to a handle 64 having a rebent outer section 66. The contact section 60 has an opening therein through which the axle 52 is extended as best shown in FIGURES 4 and 6, whereby the lever arm is pivotally connected to the holding arm.

The contact section further includes a proximal end portion 68 which terminates in an end edge 70. A curved outer wall 72 extends from the edge 70 and is angularly related thereto in such manner as to be substantially parallel to the end portion 34 of the body section of the holding arm when the elements are connected to an assembled chain. The wall includes an outer face 75 extended to a distance such that it is closely spaced from the side 41 when the elements are aligned as shown in FIGURE 4. The wall 72 is of a height greater than that of the end portion 68 and includes an inwardly and rearwardly inclined interior edge 74. As best shown in FIGURE 3, the lower side portion 18 of a link is adapted to frictionally engage this interior edge when the top 76 of the wall is engaged against one of the hinge elements 22, the lower side 18 of the link being normally spaced clear of the arm to avoid damage to the link upon the application of force to the lever arm.

In operation, assuming first that a link 12 is to be removed from an adjacent link 12a as shown in FIGURE 1, the link 12a is first engaged with the end 34 of the holding arm section 30. The end 34 extends through the opening 24 of the link 12a with the upper side 16 thereof bearing against the lug 40. The lever arm 58 is then pivoted to a position wherein the link 12 is engaged by the work contact section 60 with the link being engaged by the inclined interior edge 74 whereby the inclination of the link 12 with respect to the link 12a is established at such a position as to locate the links for assembly or disassembly, the hinge elements passing between the sections 26 at the selected angle mentioned above. This positions the top 76 of the curved wall against the hinge section 22. Downward force applied to the handle section 66 thus exerts an upward force against this sleeve disengaging the link 12 from the link 12a.

In FIGURE 7, an opposite mode of operation is shown wherein the link is being applied to the chain. Here, the device is inverted, employing the edge 42 of the stop lug 40 as a support base. Again, a downward force applied to the handle 32 moves the elements into engagement with one another.

Having described and illustrated an embodiment of

this invention in some detail, it will be understood that this description and illustration have been offered only by way of example, and that the invention is to be limited in scope only by the appended claims.

5 I claim:

1. A link assembly and disassembly device comprising:

a holding arm assembly;
the holding arm assembly including link engagement means and support means;
a lever arm pivotally related to the holding arm assembly; and
the lever arm having a contact section adapted to hold a link at selected inclination to the link engagement means of the holding arm assembly, the support means comprising an inverted T-bar.

2. A link handling device for use in the connection and removal of links from chains, the chain being of the type composed of a plurality of interconnected links, each link having a frame with an opening and opposite ends, an inner hinge element at one end and an enlarged outer hinge element at the other end, the link handling device comprising:

(I) A holding arm assembly comprising a body section and an extended handle section;

the body section having an outer end portion shaped to engage within the opening of the link with the hinge elements thereof laterally arranged;

the outer end portion having an upper side; a stop lug projecting from said upper side at a selected location;

an inverted T-bar comprising a support, including a stem secured to the body section and extending in a direction opposite to the lug and a cross bar; and

(II) a lever arm comprising a work contact section and an extended handle portion, the contact section being connected to the body section on a pivot axle extending therethrough, the pivot axle being aligned with said inverted T-bar;

the contact section having a proximal end portion with a curved outer wall;

the outer wall having an inclined interior edge and being of a height greater than that of the end portion and of a reduced thickness; and

the interior edge engaging a link frame whereby with one link engaged on said outer end of said body section and against the stop lug, the next adjacent link is pressed by the lever arm to force the engagement of its enlarged outer hinge element over the inner hinge element of said one link.

3. A device for assembling and disassembling the links of a chain, each link being of the type having an apertured frame provided with opposite end portions for interdigititation with adjacent links, comprising in combination,

a holding arm and a lever arm, and means pivotally connecting said arms for relative scissoring motion, said holding arm having an end portion dimensioned to project through the aperture of a link and positively locate said link in a plane transverse thereto, said lever arm having an end portion lying to one side of said end portion of the holding arm and presenting a tip and a base engageable respectively with an end and an immediate portion of a link adjacent that link held by said holding arm to positively locate it in a plane angulated with respect to said transverse plane.

4. The device according to claim 3 wherein said end portion of said lever arm extends inwardly from said base to said tip toward said end portion of said holding arm.

5. The device as defined in claim 4 including stop

means on said holding arm adjacent the terminus of said end portion thereof, thereby to axially locate a link thereon.

6. The device as defined in claim 5 including an inverted T-bar fixed to said holding arm adjacent the 5 pivotal connection between said arms.

7. The device as defined in claim 3 including stop means on said holding arm adjacent the terminus of said end portion thereof, thereby to axially locate a link thereon.

8. The device as defined in claim 7 including an inverted T-bar fixed to said holding arm adjacent the pivotal connection between said arms.
